MORRIS M. EINSON, OF YONKERS, NEW YORK, AND ARNOLD J. TANNER, OF NORTH HAVEN, CONNECTICUT, ASSIGNORS TO EINSON-FREEMAN CO., INC., OF LONG ISLAND CITY, NEW YORK, A CORPORATION OF NEW YORK

PACKING AND DISPLAY CONTAINER

Application filed February 29, 1932. Serial No. 595,696.

This invention relates to packing and display containers for merchandise and the container forming the subject of the present invention is an improvement in or modification of the container which forms the subject of a pending application Serial No. 587,458. The box covered by the previously filed application is composed of two container sections or members hinged together in a manner so that one section is brought into an angular position relatively to the other section whereby the merchandise contained therein is displayed with a tier-like effect. In the previous instance the two sections are further united together by a folding easel or support which automatically assumes the operative position when the container is opened for display purposes.

The present container is also composed of two sections which in the display position are arranged in angular relation to each other similar as in the previous instance but in the present modification or improvement, the two sections are not hinged together being separate from one another when in the closed position. Means are provided by which the two sections or box members are united together so that one member will be rigidly held in a determinable angular position relatively to the other member and the same means which unites said members together provides an easel or support for the complete container when in the set up position.

In the closed position of the improved container, the two sections are brought together top to top and both sections contain the merchandise to be packed and displayed. One of the sections when in the proper closed position lies on top and when set up stands behind the other section in a relatively angular position.

It is usual with display containers of all kinds to add a show card and another object of the present invention is to provide a display card which will be suitable for a container of this kind and this display card is designed to operate also as a cover for the top section so that its contents will not fall

out when turned upside down in the operation of opening the container.

The salient features of the present invention together with details of construction will be hereinafter more fully described with reference to the accompanying drawings, wherein—

Figure 1 is a perspective view of the improved container in the open or display position;

Figure 2 is a side elevation of the container in the closed position;

Figure 3 is a sectional view taken on line 3—3 of Figure 1 looking in the direction of the arrow *a*;

Figure 4 is a sectional view taken on line 4—4 of Figure 1;

Figure 5 is a side elevation showing one of the sections of the improved container;

Figure 6 shows a modification wherein the connecting piece for the two sections is a separate member;

Figure 7 is a plan view of the blank of which the rear or top section of the container is composed;

Figure 8 is a plan view of another blank of which the front or bottom section is composed; and

Figure 9 is a modification of a separate member employed for uniting the container sections together.

Referring to said drawings more particularly Figures 7 and 8 illustrating the blanks of which the improved container is composed. These blanks are employed for making a container of a conventional kind which is commonly used in practice. Various other boxes known and also in common use may be employed in carrying out the present invention and it is to be understood that for each style or type of box a suitable blank would be employed. The blanks shown in the accompanying drawings are particularly suitable in carrying out this invention for this construction of box lends itself admirably to permit applying thereto the salient features of the present invention. Said blanks and the respective sections are designated by the characters A and B, blank A being employed in the construction of the

box section which hereinafter for convenience will be termed the top or rear section. The other blank B is employed in the construction of the other section which will be called the lower or bottom section. Both blanks aforesaid are divided into a number of portions by horizontal and vertical score lines *b* and *c* so as to define portions which are folded to form the respective box section. 10 These portions are indicated by different reference letters and the parts so indicated can be identified in the set up construction by means of these reference letters.

Both of said blanks have the central portion 1 and double folding portions 2-3 extending laterally therefrom, the ends of the portions 3 being scored to provide folding ends 4. In blank A said portions 2-3 fold over flaps or tongues 5 which extend from sections 6-7 forming respectively the front and rear walls of the box sections. To retain the flaps or portions 3 in place the folding ends 4 are engaged by suitable retentive means for example such as tabs 9 cut 25 from the bottom or central portion 1 of the blanks.

Blank B is substantially the same as blank A except that another portion 10 is added to form a double back wall and this portion 10 20 carries the extensions 8 which are folded under the portions 2-3. In blank B the portions 2 have tongues 11 extending therefrom and these tongues lie in alignment with the portion 7 but are separated therefrom. 35 Said tongues 11 are connected to said portions 2 on a score line *d* which permits of folding of the tongues for the purpose hereinafter described.

The blank A forming the top or rear box section has an extended portion 12 which provides a double front wall and at the opposite end of the blank another extension 13 is carried. The latter extension forms a cover for the upper box section and which cover is adapted to be folded to form a display card for the container. The extension 13 has side wings 14 and tongues 15 extending from said wings providing retentive means for holding the folded cover in a proper display position.

When the blanks are in the folded position to form the respective container sections, the four corners of the sections are open in such a manner that it is possible to insert 55 the tongues 11 and 15 between the double folding portions 2-3. The portions 16 of tongues 11 can therefore be inserted between said portions 2-3 of box section A and thus when both tongues 11 of section B are inserted, the section A will be supported in an angular position as shown in Figure 1. The angle of the portion 16 of tongue 11 will determine the angular position of the box section A and it will be noted that these 65 tongues are retained in position by friction

and this means the rear box section A is retentively and rigidly held in the display position.

In the closed position of the improved container the tops of the container sections 70 are brought together with the tongues 11 folded against the back wall of section B and the ends 16 may be inserted within the section A to keep the tongues 11 in place. In the closed position of the container the 75 cover extension 13 is closed and the wings and tongues are inserted between the merchandise and the side walls so as to retain the cover in place. The upper section being 80 so closed there is no possibility of the contents falling out should the container be improperly inverted in the opening of the box.

The operation of setting the box up into the display position is comparatively simple for all that is required is to make the connection between the two sections by inserting the tongues 11 in the proper place, opening the cover and inserting the retaining tongues and wings 14-15 in place. By 85 this retaining means the display card is rigidly held in the proper display position relatively to the container.

In the example described above it will be noted that the connecting tongues or members 11-16 are integral with the blank of which the front section is composed. In Figure 6 a modification is shown wherein the connecting members 11 are separate pieces having the extensions 16 as before 90 with the additional extension 17, the latter being inserted and held within the front section B of the container. In this example the extension 16 has the rounded edge 18 so as to permit swinging of the supported 95 rear section A into various angular positions as desired. With the separate connecting means heavier stock may be used than when the connecting means is composed of an integral part of the blank. This is an advantage when heavier merchandise is carried by the rear supported box section.

In Figure 9 a further modification of a connecting device is shown whereby the connecting member may be blanked out from 115 the same sheet as the box blank and to obtain the required rigidity said member is doubled over on the crease line *e* so as to form a member of double thickness. With this modification the connecting member 120 may be printed or decorated along with the prepared container blank and being doubled over as described, it is not necessary to provide right and left members as would be necessary when these devices are made of 125 single sheet board printed on one side only.

Various modifications may be made in carrying out the details of the invention hereinbefore described and it is to be understood that any modification coming fairly 130

within the terms of the appended claims shall be covered thereby.

We claim:

1. A container of the class described comprising a container section having end walls, tongues projecting rearwardly from said walls, a companion section having double walls, said tongues being retentively held between said double walls, and said tongues 10 operating as a support for one section and connecting means for both sections.

2. A container of the class described comprising a container section having end walls, tongues projecting rearwardly from said 15 walls, a companion section having double side walls, said tongues being so shaped as to support the latter section angularly with respect to the other section when said tongues are inserted between said double 20 walls.

3. A container of the class described comprising companion container sections both having double walls, tongues projecting rearwardly from the walls of one section, 25 said tongues operating as a support for one section and as connecting means for both sections, and said tongues being angular extensions of separate pieces frictionally held between said double walls of the supporting 30 section.

4. A container of the class described comprising two sections composed of separate blanks, said blanks both being divided into portions by crease lines to form the bottom, 35 side, front and back walls of the sections, the side wall forming portions having extending flaps folding over inwardly folding tongues extending from the other wall forming portions to provide double walls for the 40 container sections, said flaps being secured

to retain the sections in the set up condition, connecting tongues extending rearwardly from said side forming portions of one section constituting the supporting section, said tongues being so shaped and received 70 between the double walls of the other or supported section whereby both sections are united together and the supported section is held in an angular position relatively to the supporting section.

5. A container of the class described composed of a pair of sections, one section being supported by the other, the supported section having double end or side walls, means for uniting both sections and supporting the supported section in an angular position relatively to the supporting section, and said means comprising angular disposed tongues projecting rearwardly from the supporting section at the back thereof and frictionally held between said double walls of the supported section.

6. A container of the class described composed of a pair of sections constituting a supporting section and a supported section, 90 both sections having double end or side walls, means carried by the supporting section uniting both sections and supporting the supported section in an angular position relatively to the supporting section, said 95 means comprising tongues projecting rearwardly from the supporting section at the back thereof and frictionally held between the double side walls of the supported section, a covering flap extending from the rear 100 wall of the supported section and means for retaining said covering flap in both the closed and erect position thereof.
